UNITED STATES PATENT OFFICE

94,320

DESIGN FOR A BUILDING

James M. Workman, Winnsboro, S. C.

Application May 23, 1934, Serial No. 51,900

Term of patent 14 years

To all whom it may concern:

Be it known that I, James M. Workman, a citizen of the United States, residing at Winnsboro, in the county of Fairfield and the State of South Carolina, have invented a new, original, and ornamental Design for a Building, of which the following is a specification, reference being had to the accompanying drawing, forming a part thereof.

Figure 1 is a sectional plan view showing a

section of the building showing my new design and taken on line 1—1 of Figure 2; and

Figure 2 is a view in elevation of a circular building showing my new design.

I claim:

The ornamental design for a building, as shown.

In witness whereof, I have hereunto set my hand at Washington, D. C., this 23rd day of May, 1934.

JAMES M. WORKMAN.
